UNITED STATES PATENT OFFICE.

OLIVER D. WOODRUFF, OF SOUTHBURG, CONNECTICUT.

TUBULAR LANTERN.

SPECIFICATION forming part of Letters Patent No. 408,782, dated August 13, 1889.

Application filed January 26, 1889. Serial No. 297,657. (No model.)

To all whom it may concern:

Be it known that I, OLIVER D. WOODRUFF, residing at Southington, in the county of Hartford and State of Connecticut, have invented 5 certain new and useful Improvements in Tubular Lanterns; and I do declare the following to be a full, clear, and exact description of the same, reference being had to the accompanying drawings, which form a part 10 of this specification.

My invention relates to an improvement in tubular lanterns, the object being to simplify and cheapen their construction and to increase their convenience in use over lanterns 15 of this class as heretofore made.

With these ends in view my invention consists in a tubular lantern having certain details of construction and combinations of parts, as will be hereinafter described, and 20 pointed out in the claims.

In the accompanying drawings, Figure 1 is a view in front elevation of a lantern embodying my invention. Fig. 2 is a view perspective thereof with the globe removed. Fig. 3 is a 25 broken view in vertical section through the burner-plate, the two guide-tubes, the lifting-spring, and the base of the lantern. Fig. 4 is a broken view in perspective showing how the locking-finger of the burner-plate co- 30 operates with the loop-shaped locking-spring to form a guide for the plate in its vertical movements, and Fig. 5 is a detached view in central transverse section of the burner-plate through the globe-retaining devices thereof.

The lantern herein shown is provided with 35 a base A, which contains the font, draft-tubes B B, a stationary central-draft tube C, a globe-cap or dome D, rigidly secured to the lower end of such tube, and a burner E. The lantern is also provided with a perforated burner-plate F, having a central opening adapting it to fit over the burner and forming the lower support for the globe G of the lantern. Two parallel globe-retaining devices H and I, extending in length transversely to a line drawn 40 diametrically across the plate, are secured to the said plate at opposite points thereon in position to stand up within the lower end of the globe when the same is in place. These 45 retaining devices are rigidly secured to the plate, and, as herein shown, are made of wire, 50 which, I would have it understood, may be replaced by any material suitable to the purpose.

The retaining device H, which may be called 55 the "outer" retaining device, because it is on that side of the lantern from which the globe is introduced and removed, virtually consists of a loop of wire standing above the edge of the plate and bent outward, so as to permit 60 the edge of the globe to be slipped or caught under it, this device forming a virtually rigid point of purchase, as it were, for the operation of the globe.

The inner retaining device I, so called because it is located on that side of the lantern which is opposite from the side thereof from which the globe is introduced and removed, consists of a loop standing up a little higher than the outer retaining device and having 70 its cross-piece bent to form an outwardly-projecting finger, the whole device being adapted to spring back when the globe is pressed down over it and to then recover and engage its finger with the globe, which it assists in holding in place. By arranging the retaining devices to extend in length transversely to a line drawn diametrically across the plate, and hence to present their length to the globe, a 75 much better grip is secured therefor than 80 when they are arranged parallel with a line drawn diametrically across the plate, as has heretofore been done. The loop of the device H and the finger of the device I constitute, as it were, long gripping-faces, and, being arranged for lengthwise presentation to the globe or guard, hold the same very firmly. These retaining devices co-operate 85 with a laterally-yielding globe-holder J, adapted to support and guide the upper end 90 of the globe and to permit such end of the globe to play up and down through it. As herein shown, this globe-holder is made from a single piece of wire bent to embrace more than half of the circumference of the globe, 95 then back upon itself at the ends of such bent portion, then upward and rearward for attachment to the under face of the stationary globe-cap and then downward to form braces consisting of the ends of the wire, 100 which are soldered or otherwise fastened to the curved portion of the holder at a point

sufficiently back of the open side thereof to effectually brace it under the strain of introducing and removing the globe. The open side of the curved portion of the said support 5 faces toward the outside of the lantern and so stands above the outer of the two globe-retaining devices upon the burner-plate. This plate is automatically lifted by a spiral spring K, inclosed within a tube L, depending 10 from its edge and telescoping in a larger tube M, standing up from the base of the lantern. These two tubes confine the burner-plate to vertical movement and prevent its tilting or rotation around the burner.

15 The plate is locked in its normal or depressed position against the lifting-power of the spring by means of a locking-finger N, projecting from its edge and consisting of a loop of wire having parallel sides and adapted 20 to play up and down between the parallel sides of a long loop-shaped locking-spring O, made just enough wider to permit the locking-finger to play up and down in it, as described. The ends of the wire from which 25 this locking-spring is formed are respectively fastened to the opposite faces of the adjacent draft-tube B, which is embraced by the fingers of the hand for drawing the spring back to disengage its looped lower end from the 30 upper face of the locking-finger.

Figs. 1 and 2 of the drawings show the locking-finger and locking-spring in their normal position of engagement, while Fig. 4 of the drawings shows how these parts co-operate to 35 guide and steady the burner-plate, and hence the globe, when such parts are being lifted and pulled down.

It will be understood that after the loop-shaped locking-spring has been pulled away 40 from the locking-finger the spiral spring will at once operate to lift the plate, and hence the locking-finger. Now as soon as the end of this finger has been lifted above the looped end of the locking-finger the same is let go, 45 when it flies back and embraces the locking-finger, as shown by Fig. 4 of the drawings. The burner-plate is pulled down by two operating-loops P P, formed of wire in one piece with the locking-finger and respectively extending out on opposite sides thereof, so as 50 to be readily engaged by the thumb and fingers of the hand around the adjacent draft-tube.

To put the globe into my improved lantern, 55 it is slightly canted from the vertical in the hand to permit a point in its lower edge to be slipped under the outer globe-retaining device, which now holds its lower end in place while its upper end is pressed against the 60 open side of the laterally-yielding globe-support, which opens under this pressure and receives it within its curved portion. As the upper end of the globe finds its right place in the globe-support, that portion of its lower 65 edge opposite the outer retaining device is pressed down over the inner retaining device, the outwardly-projecting finger of which

springs back to let it pass and then recovers to engage with its inner face at a point within the swell of the globe, which is now retained 70 in place both at its upper and lower ends.

To remove the globe, it is grasped near its upper end, which is pulled away from the globe-support, which expands laterally to release it, the lower end of the globe being 75 steadied meanwhile by the outer globe-retaining device, which forms a point of purchase both for the insertion and removal of the globe.

It has already been explained that when 80 the loop-shaped locking-spring is disengaged from the locking-finger the spiral lifting-spring at once lifts the burner-plate and the globe above the burner, the globe and plate being restored to their normal positions by 85 pulling down the plate by means of the operating-loops thereto provided. As the globe is thus lifted and depressed, its upper end plays up and down through the globe-support.

I would have it understood that I do not 90 limit myself to the exact construction herein shown and described, but hold myself at liberty to make such changes and alterations as fairly fall within the spirit and scope of my invention.

If desired, the stationary globe-retaining devices may be applied to the burner-plates, or the parts corresponding thereto, of burners designed for other forms of lamps than lanterns. I do not, therefore, limit myself to 100 lanterns in the use of this feature of my invention.

Having fully described my invention, what I claim as new, and desire to secure by Letters Patent, is—

1. In an oil-burner, the combination, with 105 the plate thereof, of two stationary globe-retaining devices, each consisting of a loop secured to the said plate upon which the devices are arranged for engagement throughout their length with the globe, substantially as set forth.

2. In a tubular lantern, the combination, with the plate thereof, of two parallel stationary globe-retaining devices secured to the 115 plate on which they are arranged to be engaged throughout their length by the globe, one of the devices being virtually rigid and hooked outward for the edge of the globe to be slipped under it, and the other being yielding and adapted to be sprung toward the center of the plate when the globe is applied to the plate or removed therefrom, substantially as set forth.

3. A tubular lantern having a rigid frame 125 and a stationary globe-cap or dome, an automatically-lifted burner-plate confined to vertical movement by guides, globe-retaining devices mounted upon such plate in position to stand up within the globe when the same 130 is in place thereon, and a laterally-yielding globe-holder adapted to permit the upper end of the globe to play up and down in it, substantially as set forth.

4. A tubular lantern having a laterally-yielding globe-holder for the upper end of the globe to play up and down in, attached to the globe-cap of the lantern and braced against lateral displacement, substantially as set forth.

5. A tubular lantern having a laterally-yielding globe-holder for the upper end of the globe to play up and down in, consisting of a single piece of wire bent to embrace more than half of the circumference of the globe, then bent upward and rearward at points on

opposite sides of its curved portion, and then bent downward to join such curved portion and brace the whole holder against displacement, substantially as set forth. 15

In testimony whereof I have signed this specification in the presence of two subscribing witnesses.

OLIVER D. WOODRUFF.
